JAMES WILKINSON, OF SCHENECTADY, NEW YORK, ASSIGNOR TO GENERAL ELECTRIC COMPANY, A CORPORATION OF NEW YORK.

POWER SYSTEM AND PUMP.

1,263,981.

Specification of Letters Patent. Patented Apr. 23, 1918.

Application filed January 14, 1914. Serial No. 812,140.

To all whom it may concern:

Be it known that I, JAMES WILKINSON, a citizen of the United States, residing at Schenectady, in the county of Schenectady, 5 State of New York, have invented certain new and useful Improvements in Power Systems and Pumps, of which the following is a specification.

My invention relates to power systems and 10 pumps, and more especially to internal combustion pumps in which the products of combustion act directly on the liquid. The aim of my invention is to provide a simple and economical power system and an efficient and reliable pump. Various other 15 advantages that can be secured in connection with my invention will hereinafter become apparent, and its scope will be indicated in my claims.

20 In accordance with my invention, I arrange that the pump shall supply liquid for the operation of a turbine, impulse wheel, or other type of prime mover. This can, I find, be done to the best advantage when 25 some means such as an accumulator is provided for steadyng the pressure and supply of liquid from the pump to the prime mover. It is also of advantage that the liquid discharged from the prime mover should be returned to the intake of the pump for reuse,—especially when a relatively heavy liquid such as I contemplate using is employed. The use of a dense liquid is of advantage in 30 allowing high operating speeds for the pump, and it also permits the system to be made more compact when a head of the liquid is relied on to bring about the compression needed for the most efficient operation of the pump.

40 I have hereinafter shown and described a power system and a pump constructed in accordance with my invention in which mercury is pumped and used to operate the prime mover. This apparatus is adapted to the use of almost any fuel,—as producer 45 gas, gasoline, or other gas or vapor; crude oil or other liquid; or coal dust or other solid fuel, etc. While, however, the form of apparatus shown and described is the best 50 at present known to me, and while my invention extends to this form and to its specific features and details of operation and construction and its various novel combinations and arrangements of parts, yet my invention is not confined thereto, nor to the

use of mercury, but can be carried out in other ways by means of other and lighter liquids,—including water, for example.

In the accompanying drawings, Figure 1 is a sectional view of a pumping system and 60 a pump constructed in accordance with my invention, various parts of the apparatus being broken away to bring the whole conveniently within the limits of the paper, and various parts being shown more or less 65 diagrammatically. Fig. 2 is a detailed view of the cam and associated means for operating the inlet and exhaust valves; Fig. 3 is a similar view of the cam and associated means for operating the intake and 70 discharge valves, and Fig. 4 is a detailed view of a commutator or switch for controlling the circuit of the motor which drives the cam shaft.

The system shown in the drawing 75 comprises an internal combustion pump 1 which receives mercury or other liquid from a reservoir or source 2 through a conduit 3 and discharges the same through a conduit 4 into an accumulator 5 that affords both 80 liquid storage and air cushion space. As shown, there is a valve-controlled passage 6 leading from the upper end of the accumulator chamber 5 through which air may be introduced or drawn off. From the accumulator 5 mercury is supplied to a prime 85 mover 7 of the undershot impulse wheel type, the supply being controlled by valve means 8 under the control of a speed governor 9 driven from the motor shaft. The 90 wheel of the prime mover 7 is arranged in a suitably closed casing preferably forming a part of the reservoir 2, so that the mercury discharged from it is directly returned to the pump 1. As it is intended that in 95 this pump the necessary compression of the air, fuel, or both shall be brought about by the supply of mercury, the reservoir 2 is arranged at a height above the pump sufficient to afford an adequate head for this 100 purpose. As shown, the return conduit 3 surrounds the pump delivery conduit 4; but it will be understood that this arrangement is not essential.

From Fig. 1 it will be seen that the working 105 chamber 10 of the pump 1 is contained in an upright cylindrical casing, and that there are inlet means 11 for the introduction of operating fluid comprising air and fuel, exhaust means 12 for the discharge of 110

burned products of combustion, and mercury intake and discharge means 13 and 14 connected respectively with the return conduit 3 and the delivery conduit 4. Although under suitable conditions the combustion or explosion in the working chamber 10 can be brought about as a result of compression of the operating fluid therein, this particular pump has electric ignition means 15 at the upper end of said chamber 10 for producing or insuring ignition at the proper time. In this pump, also, the air and fuel inlet means 11, the exhaust means 12, and the mercury intake and discharge means 13 and 14 are in a manner merged or consolidated in a centrally arranged upright cylindrical structure 16 that extends from a little above the top clear through the bottom of the working chamber 10. The air and fuel inlet means 11, it will be seen, comprises an inner passage or tube within this structure 16 that extends nearly to its lower end and there communicates with air and fuel ports 17 in its wall, while the exhaust means 12 comprises the upper portion of the annular passage formed by the tube and the wall of the structure 16 and opens into the upper end of the working chamber 10 through exhaust ports 18 in said wall. In like manner, the mercury delivery means 14 comprises an inner passage or tube (in effect an upward extension of the return conduit 3) that extends a short distance above the bottom of the chamber 10 and there communicates with its interior through discharge ports 19, and the mercury intake means 13 comprises the annular passage formed by said tube and the wall of the structure 16 and opens into the chamber 10 a little above its bottom through inflow ports 20. To facilitate the starting of the pump after a period of inaction, the working chamber 10 is provided with auxiliary air and fuel inlet means 21 opening into its upper end and with auxiliary valve controlled outlet means 22 through which any excess of liquid may be drawn off from its bottom. Preferably there will be a layer 23 of water, oil, or other suitable liquid on top of the mercury in the working chamber 10 to protect the same from oxidation or the like.

The ports 17, 18, 19 and 20 and the operation of the pump are controlled by valve means of sleeve-like form encircling the structure 16. As shown, there are separate valves 24 and 25 for the air and fuel inlet ports 17 and the exhaust port 18 and a common valve 26 for the mercury intake and discharge ports 19 and 20. The means for operating these valves comprises a motor 27, a cam shaft 28 driven thereby through gearing 29, an inlet and exhaust cam 30, Fig. 2, and an intake and discharge cam 31, Fig. 3, on the cam shaft 28, and suitable operating connections from the cam

30 to the valves 24 and 25 and from the cam 31 to the valve 26. In the case of the cam 30, the connections shown (Figs. 1 and 2) comprise a lever 32 having one end fulcrumed at 33 and continually urged downward by a spring 34, this lever 32 having a roller 35 for engagement with the cam mounted on it near its middle, a rod pivoted to the movable end of said lever and a yoke carried thereby, and two rods 36 that extend down through stuffing-boxes 37 in the top of the chamber 10 and are secured to the valves 24 and 25. In the case of the cam 31, the connections comprise, similarly, a lever 38, connecting rods 39, and other associated parts (Fig. 3).

The ignition means 15, it will be seen, comprises suitably separated and insulated electrodes or spark points 40 connected by suitable wiring 41 to any suitable source of current 42 and to a commutator 43 of any approved type (Figs. 1 and 4) whose rotating element is mounted on the cam shaft 28, so as to close the circuit and cause the passage of a spark between the points 40 at the proper time.

While various modes of operation and regulation may be adopted, it is preferable to meet the varying demands of the prime mover 7 for mercury by intermittent constant speed operation of the pump 1 for varying periods at varying intervals rather than by continuous operation thereof at varying speed,—making the accumulator 5 of conveniently large capacity for this purpose. As this requires the valve operating motor 27 to operate at substantially constant speed and also requires the valve operating means to be put out of action from time to time and vice versa, it is advantageous for said motor 27 to be a constant speed electric motor. Such an electric motor can be arbitrarily controlled by any approved form of hand switch 50 in its current supply circuit 51 and it can in addition be automatically controlled by means 52 responsive to the demand on the pump 1 which when said hand switch 50 is closed (as shown) will act to open and close its said supply circuit 51 as the demand varies, so that the pump 115 will be started, and stopped as occasion requires. The demand responsive means 52 shown comprises a switch 53 in said circuit 51, a cylinder 54 opening into the air space at the upper end of the accumulator chamber 5, a piston 55 in said cylinder connected with the movable part of the switch, and a helical spring 56 between the piston and a screw plug 57 in the upper end of the cylinder that tends to force the piston 55 down 125 and close the switch whenever the air pressure in the accumulator chamber (and therefore the effective pressure of the mercury therein) falls sufficiently low to permit it to do so. Accumulation of air above the 130

piston 55 to such an extent as to interfere with this action may be prevented by making the opening in the plug 57 through which passes the rod connecting said piston 5 with the switch 53 large enough to serve as a vent.

While the dual means 50 and 52 for opening and closing the current supply circuit 51 to the motor 27 would probably meet all 10 the exigencies of operation ordinarily occurring in a more or less satisfactory manner, a little consideration will make it evident that under the action of just such means alone the pump 1 would be liable to 15 stop with both the exhaust ports 18 and the mercury inflow ports 20 open, so as to allow the working chamber 10 to become completely filled with mercury, etc., or in some other condition more or less unfavorable 20 for restarting. This difficulty can be got over, however, by arranging that such means 25 50 and 52 shall when necessary be temporarily rendered ineffective, so that the valve operating means comprising the motor 27 will never be put out of action except when 30 the pump 1 is in some definite favorable condition. As shown, this is accomplished by means of an additional or "auxiliary" current supply circuit 60 for the motor 27 arranged in parallel with the "main" circuit 35 51 and having in it a commutator 61 whose rotating part or disk 62 (Fig. 4) is mounted on the cam shaft 28. The commutator disk 62 is of conductive material but has in 40 its periphery a short non-conductive segment 63; and when the main circuit is opened by either the hand switch 50 or the auxiliary switch 53 the current supplied by 45 the auxiliary circuit 60 will run the valve 50 operating motor 27 until the commutator brushes 64 come upon this segment. As shown, the commutator 61 is so set that the pump 1 will always stop at the end of a working stroke with the ports 17, 18, 19 and 20 all closed and a fresh charge of air 55 and fuel in the working chamber 10 ready to be compressed,—this being the condition most favorable for restarting.

It will be observed that the prolonging of 50 the operation of the pump resulting from the auxiliary current supply tends to reduce the number of times it will be automatically started and stopped on light loads, since it will cause the air pressure in the 55 accumulator chamber 5 to be above that at which the automatic switch 53 will close when the pump 1 stops.

I will now describe a cycle of operation of the pump:

60 The pump 1 is shown in the condition above described in which it is left when stopped through the action of the automatic control means 52 as modified by the auxiliary current supply circuit 60. Supposing, 65 now, that the pressure falls in the accumu-

lator 5 sufficiently to cause the starting of the motor 27, the first thing that happens will be the raising of the valve 26 to open the mercury inflow ports 20. Under the head in the reservoir 2, the mercury will 70 rise in the working chamber 10 and compress the charge of air and fuel therein, the momentum acquired by the mercury in the return conduit 3 during the first part of this action causing a somewhat greater compression than the hydrostatic head would alone be able to produce. About as the mercury reaches its highest level in the working chamber 10 and the charge reaches its 75 highest compression, the ignition commutator 43 will close the ignition circuit 41 and cause the ignition of the charge; and at about the same time the valve 26 will be lowered so as to close the mercury intake ports 20 and open the mercury discharge 80 ports 19. The expansion of the products of combustion will force the mercury down in the working chamber 10 and out through the delivery conduit 4 into the accumulator 85 5, the momentum acquired by the mercury 90 during the first part of this movement acting to prolong it beyond the extent to which the mere pressure of the products of combustion would be able to carry it. About as the mercury reaches its lowest level in the 95 working chamber 10 (below the fuel inlet ports 17), the valves 24 and 25 will be raised so as to uncover the exhaust ports 18 and the air and fuel inlet ports 17 and the valve 26 will be raised so as to cover the mercury 100 discharge ports 19. Thereupon the spent products of combustion will pass out through the exhaust ports 18 at the upper end of the working chamber 10 and will be displaced by air and fuel entering at the 105 same time through the inlet ports 17 near the lower end of said chamber, the air and fuel thus exerting a scavenging action, after which the valves 24 and 25 will be lowered to close the exhaust ports 18 and the 110 inlet ports 17. Thus one cycle of operation will be completed, and the pump will be restored to its initial condition. If the pressure in the accumulator 5 has been sufficiently raised to open the automatic switch 115 53, the pump will now stop; otherwise it will operate for one or more additional cycles. In the latter case the stationary dwell of the valve 26 in the mid-position in which it covers both the mercury inflow ports 20 and the 120 discharge ports 19 may be very short or even non-existent, since the time required for exhaust and air and fuel admission will not usually be long.

If owing to the length of time the pump 1 125 has been out of operation or for any other reason it is found that mercury has leaked into the working chamber 10 past the valve 26 excessively or that the charge has leaked out to a material degree, or deteriorated in 130

any way, it may in restarting be necessary to draw off some mercury through the outlet 22 or to force in a fresh and perhaps specially rich charge through the auxiliary inlet 21, or both. Ordinarily, of course, such measures will only be necessary when the pump is started up after having been stopped by means of the hand switch 50,—or as the result of failure of the air and fuel supply, the ignition current, or the current for running the valve-operating motor 27, or the like.

10 The operation of the power system as a whole will be evident without further description, it being only necessary to remark that with the pump 1 shown the accumulator 5 should be made of sufficient capacity to take care of the considerable irregularity in its output arising from the fact that it 15 delivers only on its strokes in one direction.

20 In accordance with the provisions of the patent statutes, I have described the principle of operation of my invention, together with the apparatus which I now consider 25 to represent the best embodiment thereof; but I desire to have it understood that the apparatus shown is only illustrative, and that the invention can be carried out by other means within the scope of the 30 appended claims.

What I claim as new and desire to secure by Letters Patent of the United States, is:

1. An internal combustion pump comprising a working chamber in which the products of combustion act directly on the liquid having means for the introduction of the constituents of a combustible charge, for exhaust of spent products of combustion, and for the intake and discharge of fluid; an accumulator containing elastic fluid under pressure and receiving the liquid pumped and serving to steady the pressure and flow thereof; and means responsive to the pressure of fluid in the accumulator for starting and stopping the pump.

2. An internal combustion pump comprising a working chamber having means for the

introduction of the constituents of a combustible charge, for the exhaust of spent products of combustion, and for the intake and discharge of liquid; valve means for controlling the operation of the pump; means for operating such valve means, means for ultimately putting such operating means out of action so as to stop the pump; and means for temporarily rendering said last mentioned means ineffective so as to insure the stopping of the pump in a definite predetermined condition.

3. An internal combustion pump comprising a working chamber having means for the introduction of the constituents of a combustible charge, for the exhaust of spent products of combustion, and for the intake and discharge of liquid; valve means for controlling the operation of the pump; a motor for operating said valve means; and means responsive to the demand on the pump for controlling the supply of power to said motor.

4. An internal combustion pump comprising a working chamber having means for the introduction of the constituents of a combustible charge, for the exhaust of spent products of combustion, and for the intake and discharge of liquid; valve means for controlling the operation of the pump; a constant speed electric motor for operating said valve means; a main current supply circuit for said motor and means responsive to the demand on the pump for opening and closing it; and an auxiliary current supply circuit for said motor including circuit opening means controlled in unison with the operation of the pump so as to insure stopping of the pump in a definite condition when said main circuit is opened.

In witness whereof, I have hereunto set my hand this 12th day of January 1914.

JAMES WILKINSON.
